UNITED STATES PATENT OFFICE.

PATRICK H. BENADEF, OF PUNXSUTAWNEY, PENNSYLVANIA.

TUBE-EXPANDER.

SPECIFICATION forming part of Letters Patent No. 484,314, dated August 12, 1890.

Application filed October 8, 1889. Serial No. 326,318. (No model.)

To all whom it may concern:

Be it known that I, PATRICK H. BENADEF, a resident of Punxsutawney, in the county of Jefferson and State of Pennsylvania, have invented a new and useful Improvement in Tube-Expanders, of which the following is a full, clear, and exact description.

The objects of my invention are to provide a compact and convenient implement of the class named, which will when in use lock fast to one end of a tube or boiler-flue and retain the parts in position to expand the tube inside of the boiler against the flue-sheet when the device is rotated, and afterward to flange the end of the flue, so as to return its projecting end against the outer surface of the flue-sheet.

With these ends in view my invention consists in certain features of construction and combinations of parts, which will be herein-after described, and pointed out in the claims.

Reference is to be had to the accompanying drawings, forming a part of this specification, in which similar letters of reference indicate corresponding parts in all the figures.

Figure 1 is a side view of the tool, part of the handle-bar which revolves the expander being broken off. Fig. 2 is a longitudinal section of the front portion of the device with a spring-dog in connection therewith, an edge view of the latter being shown. Fig. 3 is a cross-section of the tool, taken on the line 1 1 in Figs. 1 and 2. Fig. 4 is a transverse section of the device, taken on the line 2 2 in Fig. 2. Figs. 5 and 6 are enlarged side views of the end of the elongated bar which connects the expander-shell with the spring-dog that engages the opposite end of a flue. Fig. 7 is a transverse section of the part shown in Figs. 5 and 6, taken on the line 4 4 in said figures. Fig. 8 is an end view, enlarged, of the coupling-box which connects the expander-shell with a spring-dog, indicated at lines 3 3 in Figs. 1 and 10. Fig. 9 is a cross-section of the coupling-box, taken on the line 5 5 in Fig. 10. Fig. 10 is an enlarged side view of the coupling-box. Fig. 11 is a view of the rear ends of the spring-dog and attached parts, showing a special adjustment of the latter; and Fig. 12 is a detached view of parts of the tool, showing its operation in expanding a tube in contact with a flue-sheet.

A is the body or shell of the tube-expander. It is cylindrical and of suitable length to receive a conically-tapered pin L. At its front end A³ the shell A is reduced for the reception of a sleeve I, made to fit and slide thereon. The reduced portion A³ is extended to a shoulder k, and near this point the shell A is perforated, three spaced apertures of suitable size and form being produced for the reception of the cylindrical rollers e, which are adapted to expand the flue when these are forced outwardly by the tapering or conical pin L and the shell is rotated. At the front extremity there is a threaded portion A³, formed on the shell A, and a plug G is inserted in the end of the same, the connection being made removable by threading the parts, as shown in Fig. 2, a handle-bar G' being affixed upon the plug to rotate the shell A and the parts mounted on it.

The plug G is axially perforated and threaded to receive the screw-cut end of the bar J, which is a detachable shank for the conical pin L, the connection of said parts being a T-shaped head and slot, as at n in Fig. 2.

Upon the outer terminal of the shank J a cross-handle H is secured removably by a squared reduction of the body provided to receive the similarly-perforated handle, a binding-nut h retaining the pieces together.

Integral with the front end of the sleeve I, a collar E is formed thereon, which is perforated radially at spaced intervals to be rotated by a pin wrench or lever, which can be inserted in these holes. On the opposite end of the sleeve I a hub p is formed, on which are three integral studs i, made integral with the hub and evenly spaced apart, for the reception and revoluble support of the grooved flanging - rollers D, these being secured to revolve by the nuts i', (one being shown in Fig. 3,) which jam against shoulders on the studs i, and having threaded engagement with the free outer ends of said studs.

Upon the forward threaded portion A³ of shell A a loose collar F is mounted, it being threaded and provided with radial perforations g. The collar F serves as a nut to bear against the fixed collar E, and a pin-lever inserted in the holes g may be made to turn the collar and force the sleeve I toward the

shoulder K, for a purpose which will be explained.

The end of the shell A opposite to the reduced portion A³ is threaded for the reception of a cap-nut A', said nut being made to receive the cylindrical body of the connecting-rod A², which is of such a length, proportioned to that of the flues or tubes operated upon, that a spring-dog C will be supported to engage the end of the flue opposite to the end which is being "set," as the operation of first expanding and then flanging a flue end is termed.

It is necessary for the proper operation of the implement that the rod A² should have a swiveled engagement with the nut A'. To this end a collar r is formed on the end of the rod and has contact loosely with the nut when the parts are assembled.

The spring-dog C has two diverging limbs C', that terminate in wedge-shaped enlargements C², said enlarged portions having abrupt shoulders s, produced at the junctions of the same with the limbs C'. Each limb of the spring-dog is slotted to receive the triangular blocks a, that are pivoted at a² therein, said blocks being so adjusted that angular points of the same will project slightly above the wedge-shaped ends C², these corners being so retained by engagement of flat sides of the blocks with the plate-springs a', which springs are secured longitudinally of the limbs C' on their inner surfaces. (See Fig. 1.)

An interlocking coupling-box B is furnished to connect the spring-dog C with the rod A². The box B consists of an elongated round block centrally perforated at o, of a size to receive the rod A², the end c of said rod seating in this hole as a socket. There are aligning smaller holes o', (see Fig. 8,) formed oppositely in the body of the box B, which longitudinally cut into or intersect the axial perforation o, thus affording a proper-shaped aperture for the insertion of the wings d', formed on the body of the rod A² at opposite points.

The body of the coupling-box B is perforated at d, a nearly-rectangular orifice being produced transversely of the axial perforation of the box. The front walls of the orifice are sloped from d³ to d⁴, (see Fig. 10,) thus producing cam-faces, against which the adjacent ends of the wings d' impinge when these are inserted in the longitudinal holes o' far enough to be opposite the transverse orifice d and enter the same when the rod A² is partially revolved. As the end of the rod A² is seated on the bottom of the axial hole in the box B, the revoluble movement of the rod will cause the cam-faces of the orifice d to press the end of the rod on the terminal of the socket-hole it seats in, as at c, by reason of their wedging action on the wings d', so that the rod end and box will be removably secured together. At c' the box B is reduced and prolonged as a cylindrical bolt end b, which is threaded to receive the tapped hub

end of the spring-dog C, which can be longitudinally adjusted on said bolt by revolving it. A jam-nut b', when set tight against the end of the hub, secures the dog at any desired point thereon.

In use the rod A² is provided of sufficient length, compared to that of the boiler tubes or flues, that an accurate adjustment for length of the device between the shoulders s and k may be effected by revolving the spring-dog C on the bolt end b. The dog C is thrust into the flue from the end which is to be expanded and bead-flanged, or "set," as it is termed. The compression of the limbs C' toward each other a limited distance by the insertion of the wedge-shaped ends C² will permit the projecting ends of the triangular blocks a to abut upon the flue end. This will rock the blocks a and cause them to slide against the inner surface of the flue when the device is inserted therein. The entire device is now moved longitudinally until the beading-rollers D impinge on the front end of the flue or end in which the dog was inserted. The equal divergence of the limbs C' by reason of their set and elasticity affords means for the automatic centering of the bolt end b within the flue operated upon, so that the dog C is self-adjusting and maintains the rod A², box B, and its bolt-end extension b axially coincident within the tube, dispensing with washers and nuts that require removal and replacement when a change of the tool is made from one flue to another. The adjustment of the sleeve I longitudinally by rotation of the collar F should be such that the rollers e will lie opposite the portion of the flue which is engaged by the sheet M, (see Fig. 12,) so that a rotation of the shell A by the handle-bar G' will expand the flue and force it against the edge of the sheet as the pin L is forced against the rollers by rotation of the cross-handle H. On completion of the expansion of the flue the collar F is moved toward the handle-bar G' by revolving it, and the entire device is thrust inward until the ends C² are clear from the rear end of the flue N, when the triangular blocks a are given the position shown in Fig. 11, which will permit the shoulders S to engage the flue end and hold the tool in position to commence the beading of the flue end e', which is effected by the joint action of the rollers D and feeding collar or nut F, in an obvious manner. After the beading of a flue end has been accomplished the rollers are drawn away from the bead by reverse movement of the collar F, which will allow the sleeve I to be slid forward. Then the tool is pushed through the flue rearwardly. The blocks a, being adjusted manually, will by action of the springs a' be retained in the position shown in Fig. 1, which will permit the withdrawal of the spring-dog by compression of its limbs toward each other, the inclines on the blocks a facilitating said operation.

Having thus fully described my invention, what I claim as new, and desire to secure by Letters Patent, is—

1. In a tube-expander, the combination, 5 with an expander-shell, and a sleeve having grooved rollers loosely mounted thereon and which slides on the forward portion of the shell, of a coupling-box having a threaded bolt-end extension, a connecting-rod adapted 10 to lock fast to the coupling-box and swivel in the expander-shell, and a screw-threaded spring-dog having longitudinal adjustment on the threaded bolt-end extension of the coupling-box, substantially as set forth.
- 15 2. In a tube-expander, the combination, with an expander device loosely secured to one end of a connecting-rod, and a connecting-rod, of a coupling-box to which the other end 20 of the connecting-rod is removably attached, said box having a threaded bolt-end extension therefrom, and a screw-threaded dog having two equally-divergent spring-limbs provided with shoulders on wedge-shaped terminals, substantially as set forth.
- 25 3. In a tube-expander, a dog having equally-divergent spring-limbs, which are furnished with wedge-shaped terminals and shoulders thereon to abut on a flue end, and revoluble blocks pivoted to the limbs near the shoulders, 30 which blocks have inclined faces with the ends therefrom projecting outside of the shoulders on the spring-limbs to facilitate the removal of the spring-dog from an engaged flue end, substantially as set forth.
- 35 4. In a tube-expander, the combination, with an expander-shell having exterior threads on its forward end, a loose sleeve thereon, and spaced grooved rollers loosely mounted on the inner end of the sleeve, of a screw-threaded 40 collar which bears against the outer end of the sleeve, a conical pin within the shell, means to adjust this pin longitudinally, and a screw-threaded spring-dog having two normally-divergent limbs, which engages the rear 45 end of a threaded bolt that is swivel-connected to the expander-shell, substantially as set forth.
5. In a tube-expander, the combination, with an expander device comprised of a shell, 50 spaced rollers in the shell, a taper pin, and means to adjust the pin endwise against the expander-rollers, of a connecting-rod revolvably secured to the rear end of the expander-shell, a coupling-box in which the rod is rev-
- lubly seated and made to removably inter- 55 lock therewith, a bolt-end extension from the coupling-box, and a spring-dog having two equally-divergent limbs which terminate in wedge-shaped enlargements provided with opposite shoulders, and triangular blocks piv- 60 oted to the limbs near these shoulders to permit ends thereon to project above said shoulders when the device is to be withdrawn from a flue, substantially as set forth.
6. In a tube-expander, the combination, 65 with an expanding and beading device comprised of an elongated shell, expander-rollers seated in spaced slots in the shell, a longitudinally-adjustable expanding-pin, revolv- 70 able spaced grooved rollers radially arranged on the shell to engage a flue end with their peripheries, and means to move the pin and revolve the shell, of a coupling-box perfor- 75 ated axially and apertured transversely, so as to have interlocked connection with the winged end of a connecting-rod, a connect- 80 ing-rod loosely secured to the rear end of the expander-shell and provided with wings that enter the coupling-box apertures, and a spring-dog having two equally-divergent 85 spring-limbs having shouldered and wedge-shaped enlargements on their ends, and tri- 90 angular blocks pivoted to the spring-limbs near the shoulders, so as to project their ends above the shoulders when they are to be with- 95 drawn from a flue, substantially as set forth.
7. In a tube expander or beader, the com- 100 bination, with a cylindrical shell having a re- duced threaded portion formed integrally therewith, a sleeve mounted on the forward portion of the cylindrical shell, three grooved rollers radially and revolvably supported at spaced intervals near one end of the sleeve, and an integral collar formed at the opposite end of the said sleeve, of a tapered or coni- 105 cal pin removably attached to an elongated shank, which is held concentric with the shell, a shank, a handle-bar to revolve the shell, a cross-handle to propel the pin end- 110 wise, and three cylindrical expanding-rollers seated in spaced holes in the shell and in contact with the conical pin, substantially as set forth.
